10 Claims. (Cl. 165—166)

ABSTRACT OF THE DISCLOSURE

A heat exchanger including a plurality of identical, generally rectangular, flat flow plates. Each plate has a lip extending around its perimeter and a gasket secured to the lipped side of each plate. To secure the gaskets, the plate may have a plurality of spaced integral gasket keys and the gaskets have mating apertures. The gaskets have flow apertures which mate with the flow apertures in the plate and barriers surrounding each flow aperture. Slits are provided in a mating pair of barriers to permit flow from one end to the other. The gasket is provided with fingers which form a tortuous path from one end of the plate to the other end.

Background of the invention

This application is a continuation-in-part of my co-pending application S.N. 612,220, filed Jan. 27, 1967, now abandoned, and entitled "Plate-Type Heat Exchanger." This invention relates to a plate-type heat exchanger.

In numerous fluid processes it is necessary to either heat or cool one of the fluid streams. Various types of heat exchangers are used for this operation. One type that is often used is the plate-type heat exchanger which is formed of a multiplicity of plates clamped together in spaced side-by-side relation. The space between the plates provides a flow path on each side of the plates. As a rule, a pair of passages is provided for each flow stream. The passages are arranged so that, alternately, one flow stream passes through the passages in the plate and the other stream flows between the plates. Accordingly, one stream flows along the opposite side of the same plate in heat exchange relation. In order to obtain a good heat exchange relation, the flow streams usually follow a tortuous path and flow contra to each other.

In certain processes the heat exchange requirements are quite strenuous. For example, in the continuous distillation of sea water, the sea water feed stream which may be at a rate of 3 to 4 gallons per minute is raised from ambient temperature to approximately 200° F. In such distillation units efficiency is of paramount importance and it is very desirable that all heat be properly utilized. In such processes there may be two heated discharge streams and it is preferable that both be utilized to raise the temperature of the cold sea water feed stream. One of the heated streams is distillate which is potable water and the other is heated sea water. Naturally, the two heated streams cannot be combined and it is essential that they be kept separate throughout their travel through the heat exchanger. Moreover, in view of the corrosion characteristics of the feed stream, which is sea water, and one of the heated streams, which is heated sea water, it is essential that special precaution be taken to avoid corrosion. Accordingly, it is essential that the heat exchanger be so designed that there is no possibility of mixing the streams and that crevices and other features which could increase the likelihood of corrosion be avoided. In view of the large amount of flow involved, it is essential that precautions be taken to prevent the blow-out of the gaskets which are sandwiched between

2

the plates of the heat exchanger. It has been customary to cement the gasket to one side of the plates. The cementing is in many respects a time consuming task and if not carefully executed can result in gasket blowout or crevice corrosion. While there are many commercial-type plate heat exchangers available, there are no known satisfactory commercial plate-type heat exchangers for corrosive service utilizing compound streams.

The present invention is designed to provide a plate-type heat exchanger which utilizes compound heated streams to heat a cool feed stream, and which is so designed that gasket blowout is prevented and corrosion minimized. Moreover, the present invention provides a plate-type heat exchanger in which the cementing of gaskets between plates is eliminated.

Summary of the invention

The plate type heat exchanger of the present invention is formed of a plurality of identical, generally rectangular, flow plates having a generally flat surface except for a lip extending around the perimeter of a plurality of gasket keys. Each plate is provided with spaced apertures located adjacent each longitudinal end. The apertures form pairs to provide flow paths for different flow streams. A gasket having apertures mating with the apertures in the flow plates is secured to the lipped side of each plate. The gasket has apertures which mate with the gasket keys in the plate. The lip provides lateral support for the gasket, thereby preventing blowout. The gasket keys lock the fingers of the gasket in place and eliminate the necessity of gluing. The gasket material forms a barrier about each aperture and provides a tortuous path from one end to the other. The tortuous path provides a long-length flow path, thereby obtaining desired flow velocity. Slits are provided in the pair of barriers controlling one of the flow streams whereby one stream can flow from an opening on one end through the tortuous path to the opening at the other end. The other streams flow directly through the aperture in such plate and gasket. The plates are clamped together in side-by-side relation with the gasket providing spacing for a flow path between plates, and gasketed passages for unopened flow streams. The plates are so arranged that one of the flow streams flows in one direction between the other flow stream which flows in the opposite direction. With the above construction it is possible to arrange the heat exchanger so that one stream will be in excellent heat exchange relation with one or more streams of a different temperature. The construction is such that the heat exchanger may be a single pass arrangement or a multiple pass arrangement. With a multiple pass arrangement flow direction plates are used to change the direction of flow.

While the preferred embodiment illustrates a heat exchanger in which there are three separate flow streams, the invention is not so limited. The lip and gasket keys may be utilized in gasketed plate heat exchangers in which there are only two flow streams.

Brief description of the drawings

FIG. 1 is an isometric diagrammatic view of a two-pass plate-type heat exchanger constructed in accordance with the present invention;

FIG. 2 is an end elevation view illustrating the clamping together of the heat exchanger shown diagrammatically in FIG. 1;

FIG. 3 is a sectional view taken on lines 3—3 of FIG. 1;

FIG. 4 through FIG. 8 are plan views of gasketed plates utilized in the construction of the heat exchanger shown in FIG. 1 with FIG. 4 being the master gasket which is utilized in all of the plates;

FIG. 5 illustrates how the master gasket is cut for one of the flow streams;

FIG. 6 illustrates how the master gasket is cut for the flow direction plates;

FIG. 7 illustrates how the master gasket is cut for the second of the flow streams;

FIG. 8 illustrates how the master gasket is cut for the third of the flow streams;

FIGS. 5A, 7A and 8A are details of FIGS. 5, 7 and 8 to more clearly illustrate the slitting of the barrier of the gasket;

FIG. 9 is a sectional view taken along lines 9-9 of FIG. 4;

FIG. 10 is a plan view of a flow plate showing the location of gasket keys;

FIG. 11 is a sectional view taken along lines 10-10 of FIG. 10 showing the gasket key; and

FIG. 12 is an enlarged plan view of a portion of the plate illustrated in FIG. 10 illustrating the positioning of gasket keys around the apertures.

Description of the preferred embodiment

Referring now to the drawings, it can be seen that the plate-type heat exchanger of the present invention is formed from a multiplicity of plates 10 which are disposed together in side-by-side relation. Interposed between the plates 10 are gaskets 12 which separate the plates 10 and provide space for a flow path between adjacent plates 10, as will be explained subsequently. The heat exchanger is so designed that all of the flow plates 10 are identical in construction and the gaskets 12 which are secured to one side of the flow plates 10 are formed from a common master gasket. Such design lends itself to economical manufacture and repair.

The preferred embodiment chosen to illustrate the invention is a two-pass exchanger and a flow direction plate 16 is disposed at the midsection to change the direction of flow. However, the same type of construction may be utilized to form a single-pass heat exchanger or a more multiple pass heat exchanger, in which case a flow direction plate 16 would be located at each level where it is desired to change the direction of flow.

Referring now to the plates 10 which are shown in more detail in FIGS. 4 through 8, it can be seen that the flow plates 10 are generally rectangular and are flat except for a downturned lip 18 which surrounds the perimeter of the plate 10, see FIG. 9. If the heat exchanger is to be used in corrosive service such as in a sea water distillation process, the plates 10 may be formed from a noncorrosive material such as 90/10 copper-nickel or other similar material. All of the flow plates 10 are provided with three spaced passages 20, 22, 24 adjacent each longitudinal end. An aperture at one end is paired with an aperture at the other end for each flow stream.

A master gasket 12 having apertures 28, 30, 32 which mate with the passages 20, 22, 24 of the flow plate 10 is secured to the lip side of each flow plate 10. The lip 18 provides lateral support for the gasket 12 preventing gasket blowout due to the pressure of the flow through the heat exchanger. The master gasket 12 has barriers 34, 36, 38 about each aperture 28, 30, 32. Between the barriers on the two ends the gasket has a plurality of fingers which form a tortuous path 40 from one end of the gasket 12 to the other. The tortuous path 40 provides a long-length flow passage thereby providing the desired flow velocity. The heat exchanger is so designed that a plate 10 having a master gasket 12 secured thereto is used throughout. Therefore, if perchance one of the plates becomes damaged it is only necessary to obtain a master plate and gasket to repair the heat exchanger.

As can be seen from an examination of FIGS. 5 through 7, the gasketed plates are provided with slits 42 in a pair of barriers to permit the flow stream from one of the apertures to flow along the surface of the

plate through the tortuous path 40. For example, in FIG. 5 there are slits 42 in barriers 36-36 which surround apertures 30-30. Therefore, the stream flowing through passage 22 in the plate can flow from passage 22 on one end of the plate 10 through the tortuous path 40 to the passage 22 at the other end of the plate 10. The plates 10 controlling the other flow streams are similarly provided with slits 42 which likewise open flow for one of the streams so that such stream can flow through the tortuous path 40 along the surface of the plate 10.

While the gasket 12 may be cemented or vulcanized to the lipped side of each flow plate 10, cementing is a tedious process and to prevent crevice corrosion care must be taken to see that there is no cement extending past the edges of the gasket material. If cementing is not carried out properly, a finger may become dislodged blocking flow through the gasketed area. Accordingly, it has been found that for many installations it is preferable to provide the flow plates with a plurality of integral gasket keys 13 which are formed in the plate 10 by stamping, see FIGS. 10-12. In such case, the gasket 12 is provided with apertures 15 which cooperate with the gasket keys 13 to lock the gasket in position. With such construction it is not necessary to cement or vulcanize the gasket 12 to the flow plates 10. It has been found that, whereas cemented gaskets may blow out at 35-40 p.s.i. gaskets secured by gasket keys 13 and lip 18 will withstand 100 p.s.i. The keys 13 and apertures 15 are so positioned on the plate and gasket that each finger is provided with proper lateral support. Keys and apertures are also provided about the barrier surrounding the flow apertures, see FIG. 11.

In order to have a two-pass heat exchanger, flow direction plate 16 is interposed in the midsection of the heat exchanger. The flow direction plate 16 has openings 44, 46, 48 only at one end with the other end remaining solid. The solid end of the flow direction plate 16 arrests flow through the gasketed passages and causes the flow stream to flow through the flow paths between the plates 10 from one side of the heat exchanger to the other. A master gasket 12 is secured to the flow direction plate 16. To utilize the heat transfer surface of the flow direction plate 16, one pair of barriers are provided with slits 42. If more passes are desired, the heat exchanger may be provided with additional flow direction plates.

As can be seen from FIG. 1, the plates 10 are positioned together in side-by-side relation with a gasketed plate controlling the first flow stream alternating with gasketed plates controlling the other two flow streams. For example, in FIG. 1 it can be seen that the feed stream which may be a cold sea water feed stream to be heated by the two heated discharge streams is positioned between the blow-down stream and the distillate stream. The gasketed plates controlling the feed stream are labelled F and gasketed plates controlling the discharge streams are labelled B and D. Therefore, the feed stream is in heat exchange relation with the two heated streams in counter-flow relation. It has been found possible to raise the temperature of a cold sea water feed stream from ambient temperature to approximately 200° F. at the rate of 3 to 4 gallons per minute in a two-pass heat exchanger constructed in accordance with the present invention.

In addition to the flow plates 10, gaskets 12 and flow direction plate 16, the completed heat exchanger has two covers 50 and 52. Cover 50 is positioned on the top of the stacked assembly of plates 10 which is shown in FIG. 1 and cover 52 on the bottom of the assembly, see FIG. 2. The covers 50 and 52 and the plates 10 have a plurality of alignment holes 54 and alignment rods 56 are run through the alignment holes 54. The rods 56 have threaded portions 58 on each end and nuts 60 are threaded thereon to compress the stacked plates 10. In order to assure proper alignment, it may be desirable to have a close fit between the rods 56 and the alignment holes 54. Care should be taken to see that all the plates 10 are brought down evenly

so that there is no bending or deformation of any of the plates 10 in order that there can be an even compression throughout to prevent any possible leakage. The gaskets 12 are secured to the bottom side of each plate 10. The gaskets 12 are also in contact with the top surface of the plate 10, underneath the gasket. The stacked assembly should be compressed sufficiently so that there is no leakage in the assembly.

Welded to the top plate 62 and bottom plate 64 are the inlet nozzles 66 and outlet nozzles 68. The top and bottom plates 62 and 64 are similar to the remaining flow plates except that there are no apertures, on one end of these plates as can be seen in FIG 1. There is one pair of nozzles for each flow stream. The nozzles 66-68 extend through openings in the covers 50-52. As can be seen, on the top there are the inlets 66 for the two heated streams and the outlet 68 for cold feed stream. On the bottom side there are the outlets 68 for the two heated streams and the inlet 66 for the cold feed stream. As can be seen, all of the outlets and inlets are located on the same side of the heat exchanger. Also, as mentioned previously, there are no passages in one end of the flow direction plate 16 and the blank end is in line with the inlet and outlet nozzles 66-68. Since the gaskets 12 are attached to the bottom side of each plate 10, it is not necessary to have a gasket attached to the bottom plate 64 as it is merely used as a closure for the first flow space. The top plate 62 is provided with its regular gasket.

Accordingly, the two heated streams flow into the heat exchanger through inlet nozzles 66 and then flow downwardly through their respective passages in the plates 10 until they contact the blank wall of the flow direction plate 16. The streams then flow out through the slits 42 in their respective barriers and flow along the tortuous path 40 between the plates to the other side of the heat exchanger, see FIG. 1. At the other side, the flow streams reform and flow through respective passages in the plates 10, through the flow direction plate until they strike the bottom cover where flow is again arrested and the two streams again spread out, flowing back through the tortuous path 40 to the other side of the heat exchanger, where they reform and flow through their respective passages in the plates 10 and thence out the outlets 68. In the meantime, the feed stream comes in from the opposite direction and follows the same course of action, flowing down through the passage formed by the openings until flow is arrested by the wall of the flow direction plate 16, at which time it spreads out through the slits 42 in the barriers and flows between the plates 10. As can be seen, the heat exchanger is so arranged that the feed stream flows between the two heated streams. Also, as can be seen, the path of the streams is a tortuous path provided by the gasket and, therefore, there is good contact for a good heat exchange relation between the streams.

While the preferred embodiment of the heat exchanger has been shown arranged as a two-pass exchanger, the principle of the invention may also be used in a one-pass heat exchanger or a more multiple pass heat exchanger, and arrangements of plates other than that shown may be used. While the construction is such that a stream of one temperature may be placed in heat exchange relation with two separate and different flow streams of another temperature, the principle of the invention may be utilized in heat exchangers having only two flow streams.

From the foregoing it will be seen that this invention is one well adapted to attain all of the ends and objects hereinabove set forth, together with other advantages which are obvious and which are inherent to the apparatus.

It will be understood that certain features and subcombinations are of utility and may be employed without reference to other features and subcombinations. This is contemplated by and is within the scope of the claims.

As many possible embodiments may be made of the invention without departing from the scope thereof, it is

to be understood that all matter herein set forth or shown in the accompanying drawings is to be interpreted as illustrative and not in a limiting sense.

I claim:

5. A plate-type heat exchanger comprising a plurality of identical plates and initially identical gaskets, each plate being substantially flat except for a lip extending around the perimeter and having at least two spaced apertures adjacent each longitudinal end, an aperture at one end being paired with an aperture at the other end, a gasket secured to the lipped side of the plate with the lip providing edge support for the gasket, each gasket having apertures mating with the apertures in the plates and having a barrier about each gasket aperture, the barrier about a mating pair of gasket apertures being at least partially removed to provide a path from one of said gasket apertures at one end of the plate to its paired aperture at the other end of the plate, the plates being clamped together in side-by-side relation with the gaskets providing a space between adjacent plates whereby fluid from a mating pair of apertures may flow between adjacent plates, remaining apertures in the plates and the gaskets providing a gasketed passage for the unopened flow stream, and inlet and outlet nozzles for each flow stream.

10. The heat exchanger specified in claim 1 wherein the flow plates are provided with a plurality of integral gasket keys and the gaskets are provided with key apertures cooperating with the gasket keys to secure the gasket to the plate.

15. The heat exchanger specified in claim 2 wherein fingers extend from opposite longitudinal edges of the gasket on an alternate basis to form a tortuous path for the flow stream from one end of the plate to the other whereby the flow on one side of a plate is in counter-opposition to the flow on the other side.

20. The heat exchanger specified in claim 3 include a flow direction plate having apertures at only one end to change the direction of flow and thereby repass the fluids past each other again in heat exchange relation.

25. The heat exchanger specified in claim 3 wherein there are three flow streams, one of a first temperature and two different flow streams of other temperatures and the plates are so arranged that one flow stream is sandwiched between the other two flow streams.

30. In a plate-type heat exchanger in which a feed stream of a first temperature is passed in heat exchange relation with a stream of a second temperature comprising a plurality of identical flow plates, each of said plates being substantially flat except for a plurality of integral gasket keys spaced about the surface of the plate, said plates having at least two sets of apertures, said sets of apertures being spaced from each other and one aperture from one set being paired with an aperture from the other set; a gasket secured to the keyed side of each plate, each gasket being initially identical and having apertures which mate with the apertures in the plate and a barrier which surrounds each gasket aperture, the gasket also having a plurality of fingers to form a tortuous flow past from one set of apertures to the other and a plurality of key apertures which cooperate with the gasket keys to secure the gasket to the plate, the gasketed plates being clamped together in side-by-side relation, at least a portion of a pair of the barriers in each gasket being removed thereby opening the gasketed passage formed by the mating apertures in the plates and the gaskets so that such stream can flow through the tortuous gasketed path between the plates from an aperture at one end to its mating aperture at the other end.

35. The heat exchanger specified in claim 6 wherein the plates are provided with peripheral lips to provide additional lateral support for securing the gasket.

8. The heat exchanger specified in claim 6 wherein there are three flow streams, one of a first temperature and two different flow streams of another temperature and the plates are so arranged that the first flow stream is sandwiched between the other two flow streams.

9. The heat exchanger specified in claim 6, wherein the fingers forming the tortuous flow path extend inward from opposite sides of the gaskets on an alternate basis so that the flow on one side of a plate is countercurrent to the flow on the other side of the plate.

10. The heat exchanger specified in claim 6, wherein slits are made in the barrier to form the flow path and the portion of the barrier remaining has key apertures to cooperate with the gasket keys to secure said portion of the gasket to the plate.
